ABRADING WHEEL

Elbert B. Hubbard, Sumter, S. C., assignor to
Williams Furniture Company, Sumter, S. C., a
corporation of South Carolina

Application March 23, 1940, Serial No. 325,493

4 Claims. (Cl. 51—194)

This invention relates to a rotary sanding wheel which is used in connection with the manufacture and finishing of furniture and the like.

More specifically the invention relates to a sanding wheel having a sanding strip secured to the periphery thereof, said securing means being unique in construction and very effective so as to permit easy insertion or removal of the sanding strip on the wheel.

10 It is an object of this invention to provide a sanding wheel upon which a sanding strip is adapted to be mounted and cantilevered members for holding the sanding strip in position on the wheel. The sanding wheel shown in the accompanying drawing comprises a body portion having a resilient rim with radial peripheral grooves therein upon which the sanding strip is mounted. Suitable L-shaped members are cantilevered along one side of the sanding strip at a point slightly removed from the axis of rotation. In order to secure the cantilevered members in the radial grooves, a suitable disk is employed which applies pressure to the heel of the L-shaped members thereby causing the cantilevered or free ends to press the sanding strip firmly into the radially disposed grooves in the resilient rim.

Some of the objects of the invention having been stated, other objects will appear as the description proceeds, when taken in connection with the accompanying drawing, in which—

Figure 1 is a side elevation showing my improved sanding wheel mounted on a spindle;

Figure 2 is an elevation looking at the left hand end of Figure 1;

Figure 3 is a vertical sectional view taken along the line 3—3 in Figure 2;

Figure 4 is a sectional view taken along the line 4—4 in Figure 1.

Referring more particularly to the drawing, the numeral 10 denotes a spindle or shaft which has integral with one end thereof a restricted extension 11. Mounted upon this extension is a circular body portion 12, which portion has a peripheral flange 13 in which a plurality of radially disposed grooves 14 are cut, said grooves running longitudinally of the axis of rotation. The flange 13 is integral with one side of the periphery of the body portion of the wheel. That portion of the periphery upon which there is no flange is of a smaller diameter and is designated by the reference character 15. Upon the periphery 15 is adapted to be mounted an annular resilient ring member 16, which member is, preferably, slightly wider than the width of the peripheral surface 15. In other words, when this resilient member 16 is

inserted upon the peripheral surface 15, one face thereof abuts the face 17 of the peripheral flange 13, and the opposed face of the annular resilient member 16 extends slightly beyond the adjacent face of the body member 12.

The resilient ring member 16 has a plurality of radially disposed grooves 19 therein which are adapted to coincide with grooves 14 in the peripheral flange 13. The grooves 19 are also adapted to receive a strip of abrasive material 20, said strip being normally inserted into the grooves and in a substantially doubled position in the manner shown in Figures 2 and 4. It will be noted in Figures 2 and 4 that the ends of strip 20 are overlapped in one of the radial grooves to make an endless abrasive surface.

The grooves 14 and 19 are adapted to be penetrated by one leg of L-shaped member 25 when the sanding strip is in fixed position. The other leg of the L-shaped members 25 is pivoted upon a ring 26 which ring is removed a substantial distance from the bottom of the grooves 19 in the resilient member 16, toward the axis of rotation. The purpose of removing the pivot point of the L-shaped member in this manner has an advantage in locking the members in position. This advantage will be later described. Of course it is very essential for the pivot points of all of the L-shaped members 25 to be concentric with the restricted shaft 11 and also to be concentric with a circle passing through the bottom of the grooves 19 and 14. The ring 26 is normally confined in a disk 27 by any suitable means such as screws 28, said disk being mounted upon restricted portion 11. Also, suitable radially disposed grooves 24 are provided in the periphery of disk 27 to accommodate the intermediate portion of L-shaped members 25.

It will be noted by referring to Figure 3 that the disk 27 has a bulged portion 29 integral with its right hand face which fits into a cavity 30 in the body portion 12. The body portion 12 has extending therefrom a pin 32 and this pin extends into a hole 33 which penetrates the disk 27. The purpose, of course, of this pin is to serve as an alining means by which the L-shaped members 25 will be properly alined with the slots 14 and 19 in the members 12 and 15 respectively, before the disk can be properly inserted on extension 11. It is therefore seen that the members 25 pivot about wires 26 thereby causing the free ends to be capable of moving into or out of the slots 14 and 19, so as to make it possible to secure or remove the sanding strip 20 on the periphery of the resilient ring 16.

In order to provide a suitable means whereby the free ends of the L-shaped members 25 may be held in fixed position within the radial grooves 14 and 19, a suitable flanged nut 35 has been 5 threadably secured upon the end of restricted extension 11. This disk is knurled or serrated as at 36 on its periphery which will facilitate the grip of the operator when attempting to remove or insert the flanged nut upon the shaft. Also 10 this disk is sufficiently large to contact heel portion 25a of the L-shaped members 25 in the manner shown in Figures 1 and 3 thereby causing the L-shaped members to be normally rotated to cause their free ends to move towards shaft 10. 15 Due to the fact that the heel 25a projects slightly farther to the left (Figure 3) than the other downstanding portions of the pivoted leg it is seen that as the nut 35 is tightened, the pressure exerted by the free ends of the members 25 upon 20 the bases of the radial grooves 19 will be increased. As a result, the sanding strip 20 upon the resilient member 16 will be held more firmly. The disk 27 has a bore 37 in the left-hand face thereof (Figure 3) which is concentric with the 25 restricted shaft portion 11. The purpose of this bore is to eliminate weight and also eliminate any surrounding contact surface upon the threaded end of the shaft, except such surfaces as are threadably secured thereto. When the flanged 30 nut 35 is tightened upon extension 11, the disk 27 is also forced against the face of resilient ring 16 and toward body member 13. A nut can be placed on extension 11 in cavity 37 to confine the disk 27 against member 12 if desired. 35 It is therefore seen that I have provided an abrasive tool comprising a rotatable wheel having a wearing strip removably mounted thereon, said fixing means comprising a plurality of cantilevered bars which penetrate grooves in the periphery of the wheel and press the wearing strip in contact therewith at spaced intervals. The apparatus is very simple and easy to operate due to the fact that it is only necessary to manipulate the nut 35 in order to remove the strip 40 and replace it with a new one. 45 In the drawing and specification, there has been set forth a preferred embodiment of the invention, and although specific terms have been employed, they are used in a generic and descriptive sense only and not for purposes of limitation, the scope of the invention being set forth in the appended claims.

I claim:

1. In a sanding wheel, a body portion, an annular flange extending from one edge of the periphery of the body portion, said flange having transverse grooves therein, a disk-like retaining section having grooves therein, a resilient rim section fitted on the body portion between the flange and the retaining section and having transversely disposed grooves, the grooves of the

resilient section being in direct horizontal alignment with the grooves of the annular flange of the body portion and grooves of the retaining disk, L-shaped members disposed in the grooves in said disk-like retaining section, and being pivoted to the disk a substantial distance below the base of the grooves in said resilient rim section, the free end of the L-shaped members being adapted to penetrate the grooves in the resilient section and in the peripheral flange and means for engaging one leg of said L-shaped members to hold the free end thereof in said groove.

2. A sanding head including a body portion having a peripheral flange, a radially grooved resilient rim held in the angle between the periphery and flange of the body portion, retaining disk normally disposed adjacent one face of said body portion and also one face of the resilient rim to hold it in position against the flange, a wearing strip mounted on the periphery of said resilient rim and means for pressing said wearing strip in close contact with said resilient rim at spaced intervals, said means including a plurality of radially disposed L-shaped members pivoted in said retaining disk at a substantial distance inwardly toward the center of the disk from the point of engagement by the L-shaped member with the wearing strip and means for engaging the pivoted ends of all of said L-shaped members to hold the free ends thereof in contact with the strip and resilient rim.

3. A sanding head including a body portion having a peripheral flange, a radially grooved resilient rim held in the angle between the periphery and flange of the body portion, an abrasive wearing strip mounted on the periphery of the resilient rim and extending into the radial grooves, a retaining disk adapted to engage one face of the body portion and the resilient rim to hold said rim portion in position against the peripheral flange, radially disposed cantilevered members pivoted to said retaining disk at a point located a substantial distance inwardly toward the center of the disk from the base of said radial grooves and means adjacent the pivot points of said cantilevered members for holding the free ends thereof in engagement with said wearing strip and within said grooves.

4. A sanding head including a body portion having a peripheral flange, a radially grooved resilient rim held in the angle between the periphery and the flange of the body portion, a notched disk, L-shaped members pivoted in said notches at a point substantially removed from the base of said groove, and means adjacent said pivot points for engaging the L-shaped members for holding the free ends thereof in fixed position within the grooves.

ELBERT B. HUBBARD.
